United States Patent Office.

JOSEPH DAVIS AND SAMUEL W. FOSTER, OF LOWELL, MASSACHUSETTS.

Letters Patent No. 63,225, dated March 26, 1867.

IMPROVEMENT IN SPINNING BOBBINS.

The Schedule referred to in these Letters Patent and making part of the same.

TO ALL WHOM IT MAY CONCERN:

Be it known that we, JOSEPH DAVIS and SAMUEL W. FOSTER, both of Lowell, in the county of Middlesex, and State of Massachusetts, have invented certain new and useful improvements in the Bobbins which are used on Spinning Machines, of which the following is a full, clear, and exact description, reference being had to the accompanying drawings, making part of this specification, in which—

Figure 1 is a vertical central section.

Figure 2, a side elevation; and

Figure 3, a bottom end view.

In our said invention, the head A of the bobbin, and the quill B, are made in separate parts, and may be disconnected, if either portion is injured and needs to be replaced. The lower end of the quill B is slightly tapering from the top *a* of the head A downward, and largest at *e*, from which point to the lower end *b* a portion of the outside is removed, leaving an annular space, *c*. A slit, *g*, is sawed in the lower end of the quill upward to near the top *a* of the head A, which head has a tapering hole through it, largest at the bottom end. The lower end of this tapering part of the quill B fits the hole through the head A of the bobbin so closely that the divided parts, *d d*, of the quill are pressed firmly together. One or more bulges or enlargements, *f*, are formed on the upper portion of the quill to prevent the yarn slipping or sliding off, or upsetting, when being reeled or woven from the bobbin, as is very common with straight or slightly tapering quills. From one to two inches of the top end of the quill is also tapering, the extreme top being the smallest, and rounded to allow the yarn to twist and wind freely. Pushing the bobbin on to the spindle of the spinning machine presses the parts *d d* of the quill outward, and causes them to bind against the surface of the spindle and hold the bobbin firmly in its place without the aid of any other device, and when yarn is reeled or woven from our improved bobbin, the bulges or enlargements *f* prevent the yarn slipping or sliding, or being upset and tangled, or broken during the operation of reeling or weaving the yarn, which, with the simple and efficient method described of holding the bobbin to the spindle, are the objects of our invention.

What we claim as new, and desire to secure by Letters Patent, is—

Removing a portion of the lower end of the quill, and slitting the end, as shown at *g*, thereby forming the annular space *c*, and the parts *d d*, which act against the surface of the spindle, all substantially as and for the purpose set forth.

JOSEPH DAVIS,
SAMUEL W. FOSTER. .
